WOLDEMAR HEINITZ, OF CHEMNITZ, GERMANY, ASSIGNOR TO SCHUBERT & SALZER
MASCHINENFABRIK A.-G., OF CHEMNITZ, SAXONY, GERMANY

STRAIGHT KNITTING MACHINE

Application filed October 30, 1931, Serial No. 572,153, and in Germany October 30, 1930.

My invention relates to straight-knitting machines such as machines of the Jacquard petinet type, and more particularly to the narrowing device for such machines.

5 If stockings are knitted to fashion on a Jacquard petinet or other straight-knitting machine, the narrowing comb which extends all over the width of the section and is equipped with a tickler needle per frame 10 needle effects not only the patterning throughout the article but also the narrowings at the shank, the calf, the heel and the point, and the widening at the heel. However, as the narrowing comb transfers the 15 loops only in a given direction per operation it is necessary to provide means for performing separate movements for all narrowing and widening operations, i. e., a separate movement must be performed for narrowing 20 or widening in each row of loops (from the right and from the left in narrowing and to the right and to the left in widening).

Obviously the separate movements of the narrowing device involve complication and 25 loss of time, and it is an object of my invention to eliminate these drawbacks.

To this end I provide the usual narrowing comb extending all over the width of the section, with a tickler needle per frame 30 needle which is adapted to serve for patterning as well as for widening and narrowing, but according to my invention I divide the comb and provide means for selectively displacing its parts in unison and in opposite 35 directions.

In a divided narrowing comb the parts will move in unison and in the same direction during patterning but in opposite directions perform their movements for narrowing 40 and widening.

By dividing the narrowing comb in the manner described and by controlling its parts as required the several operations are performed very rapidly by very simple 45 means while all the auxiliaries required if a separate pair of means for narrowing and widening are provided in addition to the patterning comb, such as a pair of separate narrowing spindles, transmitting means, 50 four separate tickler bars, stops, and means

for throwing in and out the means with respect to the patterning comb are dispensed with.

In the drawings affixed to this specification and forming part thereof a narrowing device having a divided comb is illustrated diagrammatically by way of example.

In the drawings Fig. 1 is an elevation of the device in the patterning, and

Fig. 2 is an elevation in the narrowing and widening position of its divided comb.

Referring now to the drawings, 1 is a portion of the frame of the machine which is equipped with means for guiding two independently movable operating bars 2 and 3. 4 and 5 are the two parts of the narrowing comb which are attached, respectively, to the bars 2 and 3 and equipped with the usual tickler needles, and 6 is the frame-needle bar.

In the position illustrated in Fig. 1 in which the two parts 4 and 5 of the narrowing device are abutted at their inner ends for patterning, the overall width of the device is equal to the width of the bar 6 which in turn is equal to the width of the given section of goods.

The outer ends of the operating rods 2 and 3 are equipped with dogs 7 and 9 and springs 8 and 10, respectively which tend to separate the two parts 4 and 5 of the comb.

11 is a cam shaft in the frame of the machine to which rotation is imparted by any suitable means, not shown. 12, 13 and 12', 13' are pairs of stepped cams which are mounted to slide on opposite ends of the shaft 11. Each cam has a neck ring at one of its ends, with double-armed operating levers 15, 16 fulcrumed at 14, and 15', 16' fulcrumed at 14' for shifting the cams 12 and 12', respectively, and double-armed levers 19, 20 fulcrumed at 18 and 19', 20' fulcrumed at 18', respectively, for shifting the cams 13 and 13', respectively. The outer arms 16 and 16' of the levers for the cams 12 and 12' are connected to a patterning device, not shown, by means of rods 17 and 17', respectively, and the outer arms 20 and 20' for the cams 13 and 13' are connected to 100

the patterning device by rods 21, 21', respectively.

Each pair of cams control a pair of stepped slides which in turn control the operating bars 2 and 3 of the cam parts 4 and 5, as follows: 23 and 23' are transposing slides with a single step at one end and with the other end adapted to bear on the cams 13 and 13', respectively, and 25, 25' 10 are rollers for supporting the slides at their stepped outer edges. 22 and 22' are narrowing slides with, for instance, four steps at one end at their inner edges and with the other end adapted to bear on the 15 cams 12 and 12', respectively, their straight outer edges bearing on the straight inner edges of the transposing slides 23 and 23', respectively. 24 and 24' are rollers inserted between the dogs 7 and 9, respectively, and 20 the stepped portion of the corresponding narrowing slide.

In the position illustrated in Fig. 1 the transposing slides 23 and 23' bear on their rollers 25, 25' with their unstepped portions 25 and the springs 8 and 10 are compressed by the narrowing slides 22 and 22', through the rollers 24 and 24'. The comb parts 4 and 5 are abutted at their inner ends and move in unison and in the same direction 30 for patterning. The rods 21 and 21' have been operated by the patterning device, not shown, so as to move the highest step of the cams 13, 13' into alignment with the corresponding transposing slides 23, 23'. The 35 narrowing slides 22, 22' bear on the central steps of their respective cams 12, 12'. The cams are displaced by means of the tension members 17 and 17' for shifting the comb parts in unison and in the same direction as 40 required for the patterning.

The comb moves from the normal position in Fig. 1 as a unit, i. e., with its parts 4 and 5 abutted at their inner ends, to the left or to the right for one needle, or for two 45 needles, as required by the pattern. If the rod 17 is moved to the right the cam 12 is moved to the left and the slide 22 bears on a lower step of the cam 12. At the same time the rod 17' moves to the right but 50 shifts the cam 12' in inward direction so that the narrowing slide 22' bears on a higher step of this cam. If the rods 17 and 17' are moved in the opposite direction, the slides 22, 22' will bear on a lower step of 55 their cams 12, 12' and in any case the displacement of the slides is translated into reciprocation of the comb parts 4 and 5 as a unit in a given direction for one or two needles.

60 If it is desired to perform widening or narrowing operations by the parts 4 and 5 of the comb the rods 21 and 21' are moved inwardly and shift the cams 13 and 13' outwardly, causing the transposing slides 23 65 to bear on the lower steps of the cams. The

outer edges of the slides now move off the rollers 25, 25' with their steps, as shown in Fig. 2, and the springs 8 and 10 separate the parts 4 and 5. In the example illustrated it has been assumed that the outward movement extends over two needles at both sides so that four frame needles are exposed between the separated parts 4 and 5. The parts are now reciprocated in opposite directions and away from each other by 75 means of the bars 17, 17' and the cams 12, 12'. By moving the cams 12 and 12' outwardly for one or two of their steps, the narrowing slides 22 are moved down for one or two of the steps at their inner edges and the sides of the goods are widened for 80 one or two needles. By moving the cams 12, 12' inwardly the narrowing slides 22 and 22' are raised for one or two steps and the sides of the goods are narrowed for one or two 85 needles.

The steps on the narrowing slides 22 and 22' may be so designed that the parts 4 and 5 of the comb are moved apart for one or more needles per step.

90 It is understood that the machine which has been shown and described is only an example. The gist of my invention is that it is possible to pattern goods, for instance, stockings, throughout the width of the leg (with the exception of a few unpatterned edge loops) with one comb and with the same comb and in a single operation to narrow and to widen the goods simultaneously at both sides. Obviously it is also possible 95 to pattern within the reach of each comb part 4, 5 during the narrowing or widening operations within the limits of the comb movement.

100 I wish it to be understood that I do not desire to be limited to the exact details of construction shown and described, for obvious modifications will occur to a person skilled in the art.

105 In the claims affixed to this specification no selection of any particular modification of the invention is intended to the exclusion of other modifications thereof and the right to subsequently make claim to any modification not covered by these claims is expressly reserved.

110 I claim: —

115 1. A straight-knitting machine comprising a divided narrowing comb extending all over the width of the fabric to be knitted on the machine, and means for selectively shifting the parts of said comb longitudinally in unison and in opposite directions.

120 2. A straight-knitting machine comprising a divided narrowing comb extending all over the width of the fabric to be knitted on the machine, a pair of slides per part of said comb, with two of their edges in sliding contact with each other, a step on one of said slides, a fixed stop adapted to co- 125

operate with said step, steps on the other slide adapted to act on said comb parts, and means for varying the position of said slides with respect to each other, said stop 5 and said comb parts.

3. A straight-knitting machine comprising a divided narrowing comb extending all over the width of the fabric to be knitted on the machine, a rod per comb part mounted 10 to slide on said machine, stepped slides adapted to displace said rods, and means for reciprocating said slides.

4. A straight-knitting machine comprising a divided narrowing comb extending all 15 over the width of the fabric to be knitted on the machine, a rod per comb part mounted to slide on said machine, stepped slides adapted to displace said rods, and means for varying the action of each slide on its 20 rod.

5. A straight-knitting machine comprising a divided narrowing comb extending all over the width of the fabric to be knitted on the machine, a rod per comb 25 part mounted to slide on said machine, stepped slides adapted to displace said rods, and stepped cams for reciprocating said slides.

6. A straight-knitting machine comprising a divided narrowing comb extending all over the width of the fabric to be knitted on the machine, a rod per comb part mounted 30 to slide on said machine, stepped slides adapted to displace said rods, a cam shaft, stepped cams mounted to slide on said shaft for reciprocating said slides, and means for 35 shifting said cams on said shaft with respect to said slides.

In testimony whereof I affix my signature.

WOLDEMAR HEINITZ.
